UNITED STATES PATENT OFFICE.

EUGENE T. SPECHT, OF CHICAGO, ILLINOIS, ASSIGNOR OF ONE-HALF TO
ERNEST A. EASTMAN, OF CHICAGO, ILLINOIS.

CAST-OFF CONNECTION FOR SUSPENDERS.

SPECIFICATION forming part of Letters Patent No. 705,621, dated July 29, 1902.

Application filed March 11, 1902. Serial No. 97,750. (No model.)

To all whom it may concern:

Be it known that I, EUGENE T. SPECHT, a citizen of the United States, residing at Chicago, in the county of Cook and State of Illinois, have invented certain new and useful Improvements in Cast-Off Connections for Suspenders, &c., of which the following is a specification.

My invention is concerned with certain new and improved constructions of the connections between the main strap or web of suspenders and the tabs whereby the latter can be instantly "cast off" when desired, and is designed to produce a device of the class described which shall be extremely simple in its construction, easily and quickly operated, and which, most of all, shall be durable.

To illustrate my invention, I annex hereto a sheet of drawings in which the same reference characters are used to designate identical parts in all the figures, of which—

Figure 1 is a front elevation of a suspender-end having my invention applied thereto. Fig. 2 is a front elevation of the metallic portion of the connection. Fig. 3 is a side elevation, in vertical section, on an enlarged scale, on the line A A of Fig. 1. Fig. 4 is a vertical section on the line B B of Fig. 3. Fig. 5 is a view similar to Fig. 1, but with the tab removed and showing a modified form of construction; and Fig. 6 is a central section through the metallic portion of the modified form of connection.

The main strap or web portion *a* of the suspender may of course be of any desired construction and is preferably formed with the loop at its lower end, as shown. The tabs *b* may likewise be of any desired construction, but are preferably formed with the central portions thereof rounded, as shown, to form a smooth bearing-surface which may play readily over the metallic hook, with which it coöperates.

The basis of the cast-off connection is the metallic portion *c*, the preferred form of which is shown detached in Fig. 2 and which consists of the upper horizontal cross-piece *d*, preferably provided with the ferrule or roller *e* and with which the main strap *a* coöperates. In the preferred form (shown in Figs.

1 to 4) this part *c* is formed of a single piece of wire bent into the shape shown, and the generally rectangular outline thereof is broken by the offsets *f*, which serve to reduce the width of the lower portion thereof, so that the portions *g*, which together constitute the lower cross-piece, are narrower than the upper cross-piece *e* and of the proper width to snugly accommodate the short strap *h*, which is folded about this portion and which constitutes the outer covering of the cast-off. The parts *g* are brought substantially together and the wire constituting them is then turned downward and separated to make the opening *j*, through which the eyelet *k* is adapted to pass. The wire is then brought together, as shown, and turned upward to constitute the hook *l*, which I preferably cover with the brass bushing *m* to reduce the friction between it and the tab *b*. This bushing is of the proper shape, as best seen in Fig. 4, to snugly surround the wire and be held in position thereby while presenting a concave surface from front to rear and a convex surface from side to side, so that the central portion of the tab will slide smoothly and freely over it. While I have shown this bushing as preferably constructed of thin sheet metal, such as brass, covering the outline of the hook with a smooth curved bearing-surface, it may take some other form, such as an antifriction-roller. The strap *h* is provided at its upper end with the aperture *n* and also with an aperture *o*, located about the center thereof, but nearer the upper edge. The eyelet *k* passes through these apertures and through the opening *j* and when it is headed serves to securely clamp these parts together. The fastener-head *p*, which is of the customary construction employed in this class of devices, is secured on the eyelet at the time it is headed, preferably by having the flange *q* on the base thereof interposed between the strap *h* and the flange *r*, formed on the eyelet *k* when it is riveted in place. The strap *h* is provided at its lower end with the fastener-cap *s*, which is of the customary construction and is secured to the end of the strap *h* in some suitable manner.

The operation of the device will be readily

apparent and needs no explanation. With the connections built up in this way, consisting of the single metallic piece constituting the skeleton of the entire construction, it makes an extremely simple and durable device, which cannot get out of order or be broken under the normal strains put upon this class of devices.

In Figs. 5 and 6 I have shown a slightly-modified form of construction, in which the connection *c*' is stamped up from a piece of sheet metal, having substantially the same general outline and arrangement of parts as the wire one, except that instead of having the hook with a separate bushing on the lower end thereof, the hook *l*' being made of sheet metal is easily formed with its upper surface of the same outline as the upper surface of the bushing *m*.

While I have shown my invention as embodied in the form which I at present consider best adapted to carry out its purposes, it will be understood that it is capable of some modifications and that I do not desire to be limited in the interpretation of the following claims, except as may be necessitated by the state of the prior art.

What I claim as new, and desire to secure by Letters Patent of the United States, is—

1. In a device of the class described, the combination with the main strap and the tab, of the cast-off connection therefor consisting of the single rigid metallic member having the elongated transverse opening at the top for the main strap and the opening beneath it for the eyelet and terminating in the hook, together with the strap having the fastener-cap therein, the fastener-head, and the eyelet connecting the parts substantially as described.

2. In a device of the class described, the cast-off connection consisting of the single rigid metallic member having the elongated transverse opening at the top and the opening beneath it for the eyelet and terminating in the hook, together with the strap having the two openings therein and the fastener-cap at one end thereof, the fastener-head, and the eyelet passing through the lower opening in the metallic member, the two openings in the strap and coöperating with the fastener-

head to secure the parts substantially as and for the purpose described.

3. In a device of the class described, the cast-off connection therefor consisting of the single rigid metallic member formed of a wire rod bent into shape to form the elongated transverse opening at the top and the smaller opening beneath it and terminating in the hook, together with the strap having the openings *n* and *o* therein and the fastener-cap at the bottom thereof, the fastener-head, and the eyelet *k* adapted to pass through the openings in the strap and the lower opening in the metallic member and coöperating with the fastener-head to secure the parts together substantially as described.

4. In a device of the class described, the cast-off connection consisting of the single rigid metallic member formed of the wire rod bent into shape to have the elongated transverse opening at the top with the lower portion thereof narrowed by the offsets *f*, and with the smaller opening beneath the transverse opening and terminating in the flattened hook *l*, together with the strap *h* having the openings *n* and *o* therein and the fastener-cap in the bottom thereof, the fastener-head having the flange *q*, and the eyelet *k* passing through the openings *n* and *o* in the strap and the smaller opening in the metallic member, and having the flange *r* coöperating with the flange *q* to clamp the parts together substantially as shown and described.

5. In a device of the class described, the combination with the main strap and the tab, of the cast-off connection therefor consisting of the single rigid metallic member made of wire having the elongated transverse opening at the top for the main strap and the opening beneath it for the eyelet and terminating in the hook, the bushing about said hook, together with the strap having the fastener-cap therein, the fastener-head, and the eyelet connecting the parts substantially as described.

In testimony whereof I affix my signature in presence of two witnesses.

EUGENE T. SPECHT.
